UNITED STATES PATENT OFFICE.

HENRY MCNAUGHTON, OF ERIN, ONTARIO, CANADA, ASSIGNOR TO ROBERT WOOD, OF SAME PLACE.

SURGICAL SPLINT.

SPECIFICATION forming part of Letters Patent No. 291,617, dated January 8, 1884.

Application filed October 12, 1883. (Model.)

To all whom it may concern:

Be it known that I, HENRY MCNAUGHTON, a subject of Great Britain, residing at the village of Erin, in the county of Wellington, Province of Ontario, Dominion of Canada, physician, have invented a certain new and useful Improvement in Splints for the Forearm, Wrist, and Hand, (for which a patent has been applied for in the Dominion of Canada,) of which the following is a specification.

My invention has for its object the securing of a fractured forearm in an immovable position, without causing unnecessary pain to the patient in the application of the same, and afterward when the splint is in position upon the arm.

It consists of a new surgical appliance or splint, made of any suitable material, and so constructed as to embrace the inner part of the forearm, the lower portion of which appliance terminates in a downwardly-sloping piece or palm accurately fitting the palm of the hand, and thence rises up over the wrist and along the forearm, forming a closely-fitting and easy support all along the splint.

In the accompanying drawings, Figure 1 is a face view, showing that side of the splint which is placed next the arm. Fig. 2 is a back view of the same. Fig. 3 is a longitudinal section through the line *a a* in Fig. 1. Fig. 4 is a transverse section through the line *a' b* in Fig. 1. Fig. 5 is also a transverse section, and is through the line *c f* in Fig. 1. Fig. 6 is a transverse section through the line *c' d* in Fig. 1.

Similar letters of reference indicate the same parts in all the views and in the specification.

A represents the palmar section, B the carpal section, C the interosseous section, and D the section near the superior extremity; E, a ridge fitting the interosseous space; E', an abrupt ridge, and widened to fit the palm of the hand.

Referring to the drawings, it will be seen that from the configuration of my splint it will fit the forearm accurately and easily, and that it can be applied and worn upon the arm with comfort until a complete cure is effected and the arm has become strong and well. Being well adapted to the radial curve of the arm, it maintains the integrity of the interosseous space. It also retains the hand in its normal position, and allows free motion of the fingers, and can be applied to either forearm with equal facility.

Having thus described my invention, what I claim, and desire to secure by Letters Patent of the United States, is—

In a splint for the forearm, wrist, and hand, constructed as shown and described, the combination, with the shell A B C D, of the longitudinal ridge E and the abrupt ridge E', for the purpose specified.

HENRY MCNAUGHTON.

In presence of—

W.M. CONBOY,
J. WOOD.
